UNITED STATES PATENT OFFICE.

JOHN SHERMAN SIMS, OF LONGBEACH, CALIFORNIA, ASSIGNOR OF ONE-HALF TO EDWARD RICHARD MILLAR, OF LONGBEACH, CALIFORNIA.

RAILWAY-SIGNAL.

No. 884,224.

Specification of Letters Patent.

Patented April 7, 1908.

Application filed May 22, 1907. Serial No. 375,056.

To all whom it may concern:

Be it known that I, JOHN SHERMAN SIMS, a citizen of the United States, residing at Longbeach, in the county of Los Angeles 5 and State of California, have invented a new and useful Railway-Signal, of which the following is a specification.

This invention has reference to improvements in railway signals, and its object is to 10 provide means for distant notification of the condition of the track, such, for instance, as whether the track may be open to traffic or closed to traffic by the opening of sidings or switches, and also to provide means whereby 15 signals may be transmitted from any desired point.

The invention comprises means for the visible production of signals by either day or night, the invention being more particularly 20 intended for the display of danger signals while the absence of any signal will indicate safety.

The invention is not designed primarily as a block signal system but more particularly 25 for the purpose of giving warning of the presence of a dangerous condition at a sufficiently remote point from the zone of danger to enable the engineman, in the case of a steam railway, or the motorman, in the case of an 30 electric railway, to avoid such danger.

The invention is designed to display a semaphore signal or target which by daylight will show the presence of danger, and by night the same signal will be transmitted 35 by a suitable red light.

The invention is also designed to provide any suitable number of such signals for simultaneous operation on either or both sides of the danger zone, so that an approaching 40 train or car may receive a number of warnings; thus, should the first warning be passed, others will be seen before the danger zone is reached.

The practical embodiment of the invention is shown in the accompanying drawings, forming part of this specification, in which,—

Figure 1 is a view, partly diagrammatic, of one of the signal indicating devices as applied to a switch along the line of railway. Fig. 2 50 is a plan view of the electric motor signal operating device; and Fig. 3 is a diagram of a portion of a system constructed in accordance with the present invention.

The signal indicating devices are designed 55 to be placed upon telegraph poles or other

high structures along the line of way, and in Fig. 1 there is shown a telegraph pole 1 and one of its cross-arms 2. This telegraph pole is shown contiguous to one rail 3 of a railway track and the wing 4 of a switch, but it will be understood that the telegraph pole carrying the signal devices is to be located at a considerable distance from the switch, such distance being sufficient to enable the engineman or motorman to bring the train or car to a standstill provided the danger signal is displayed. As will appear further on, there will be a number of these danger signals displayed at still more remote points, so that should the first danger signal approached be 60 passed, either from negligence or failure to observe the same, there will be several danger signals displayed before the danger zone is reached.

Mounted upon the telegraph pole, preferably under the cross-arm 2, is a box 5, suitably sealed, of course, against the elements and against malicious tampering. Within this box there is mounted an ordinary electro-magnet 6 of the horse-shoe type, and in 65 operative relation to the poles of this magnet is an armature 7 fast on an upright lever 8 hinged at its lower end in a suitable journal 9 fast on the bottom of the box. At the other or yoke end of the magnet and still within 70 the box 5 there are two standards 10 suitably spaced apart and having journaled in their upper ends a crank shaft 11 carrying a pinion 12 engaged by a rack bar 13 fast at the other end to the upper end of the lever 8. 75

Secured to the shaft 11 are two arms 14—15, one at each side of the pinion 12, approaching at their outer ends and there carrying by means of a pivot 16 a target 17 similar to the ordinary switch target or of any desirable shape. This switch target is pendently hung from the ends of the arms 14—15 85 by means of the pivot pin 16, and is movable into and out of the box 5 through a slot 18 therein.

Upon the shaft 11 there is mounted a wheel 19 having an eccentric rim, one side 20 of which is so heavy as to overbalance the wheel and tend to always maintain it in one particular position, which particular position 95 will be that which will carry the switch target 17 to the safety position. This position, in the structure shown, would mean that the switch target 17 is drawn up out of sight into the box 5, through the slot 18, while the dan- 100 105 110

ger position would be represented by the target 17 being moved into sight by being dropped below the box 5 through the slot 18, which position is the one indicated in the 5 drawings.

In Fig. 1 there is shown a switch stand 21, which, being of the ordinary type, needs no description. The arm 22 of this switch stand, by means of which the switch is thrown 10 carries a contact finger 23 arranged to make contact with a conducting stud 24. The arm 22 is electrically connected to a branch conductor 25 and the stud 24 is electrically connected to another branch conductor 26. 15 Upon each telegraph pole containing a signal mechanism, or at any other suitable point, there will be located a number of switches 27 which may be inclosed in switch boxes 28, accessible only to authorized persons having 20 a suitable key. The magnets 6 are included in an electric circuit, as will readily appear, and in series with each of these magnets there is an electric lamp 29 arranged behind suitable bull's-eyes 30 of red glass. The lamp 25 29 may be inclosed in the same box with the magnet or in another box 31 attached to said main box 5.

In Fig. 3 is diagrammatically represented one means of connecting up the signal mechanism. At some convenient point there is located a source of current represented by the battery 32. From this battery lead two 30 conductors 33-34. From the conductor 34 by a branch conductor 35 the current is led 35 to a lamp 29 and the corresponding magnet 6 and from thence to another conductor 36 extending along the line of way. All the lamps and the corresponding magnets are connected in multiple across the conductors 40 34 and 36. The switches 27 are connected by conductors 37 to the line conductors 36 and by other conductors 38 to the line conductors 33, and other switches 39 may be located at the stations or elsewhere and connected 45 by conductors 40 and 41 to the line wires 36 and 33, respectively. Or, any other suitable connections between the switches and the line wires may be used, as may be found most desirable. Now, when 50 a railway switch is so moved as to open a siding to traffic the circuit through the branch wires 25 and 26, which are connected to the conductors 37 and 38, will be from the main conductor 33 through the conductor 38 55 and branch conductor 26, the contacts 23 and 24, the branch conductor 25, the conductor 37 to the main conductor 36, thence through the magnets and lamps and back to the main conductor 34 and thence to the 60 battery 32. The magnets 6 are thus energized and the armatures 7 are pulled toward said magnets, thus causing the wheels 19 to revolve in a direction to elevate the weighted sides 20 thereof and at the same time throw 65 all the targets 17 into the position indicat-

ing danger and simultaneously light all the lamps 29. The targets are visible in daylight and the lamps at night so that when a railway switch is moved to open a siding to traffic the several signal indicating devices are set at danger so that approaching 70 trains are warned in time. On curves, the signal devices may be located at each telegraph pole, while on straight lines these devices will be located considerable distances 75 apart, depending upon circumstances. The switches 27 and 39 enable track walkers or station agents to warn trains of open switches, wrecks, washouts, runaway trains, or any other dangerous condition. When 80 the dangerous condition is past, say, for instance, when the switch has been so moved as to open the main track to traffic, or a wreck has been cleared away, or whatever may have been the element of danger is eliminated, the circuit is broken, either at the switch target or at one of the switches 27 or 39 and the magnets become deenergized. Now, the weighted side 20 of the wheel 19 causes the latter to turn by gravity to the 85 position to move the armature 7 away from the poles of the magnet and to bring the semaphores arm or target 17 into the position indicating safety, and at the same time the lamps 29, no longer being supplied with 90 current, cease to glow.

I claim:—

1. A railway signal comprising an electromagnet; a receptacle containing the same; a gravity member in the receptacle, moved 100 against the action of gravity and by said magnet when energized; a pendent semaphore or target carried by the gravity member and overbalanced thereby, said target being moved out of the receptacle and into 105 sight to indicate danger when the gravity member is moved against the action of gravity and moved into the receptacle out of sight when the magnet is deenergized and the gravity member becomes active; and an 110 electric lamp and danger indicating means coöperating therewith adjacent to but independent of the semaphore or target and in series with the magnet, said lamp receiving current when the magnet is energized. 115

2. A railway signal comprising an electromagnet; a gravity member movable against the action of gravity by said magnet when energized and consisting of a wheel with an eccentric rim, an arm actuated by said 120 wheel, a pendent semaphore or target carried by said arm, and a receptacle for the magnet, gravity member and target in which receptacle the target is normally held by the action of the electro-magnet when 125 energized.

3. A railway signal system comprising a source of current; a pair of open-circuit conductors leading therefrom along the line of way; a third conductor also leading along 130

the line of way; electrically operated signal devices branched between one of the main conductors and the third conductor; railway switch operating devices along the line of way; circuit terminals branched between the third conductor and the other main conductor; means on the railway switch operating mechanism for closing the terminals there located when the said switch is manipulated to open the siding to traffic, and electric switches independent of the railway

switches and branched between the third conductor and the said other main conductor.

In testimony that I claim the foregoing as 15 my own, I have hereto affixed my signature in the presence of two witnesses.

JOHN SHERMAN SIMS.
